CLAIM

The ornamental design for a combined skin testing and vaccinating needle design, as shown and described.

DESCRIPTION

FIG. 1 is a perspective view of a combined skin testing and vaccinating needle embodying the present invention;
FIG. 2 is a side elevational view thereof, the undisclosed opposite side being the same view;

FIG. 3 is a side elevational view thereof, taken at 90 degrees to FIG. 2, the undisclosed opposite side being the same;

FIG. 4 is a top plan view thereof;

FIG. 5 is a bottom plan view thereof; and,

FIG. 6 is a perspective view corresponding of FIG. 1 in which the handle is knurled.
